UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR

Application filed November 5, 1919. Serial No. 335,806.

To all whom it may concern:

Be it known that I, LIONEL M. WOOLSON, a citizen of the United States, and resident of Detroit, Wayne County, State of Michigan, have invented certain new and useful Improvements in Hydrocarbon Motors, of which the following is a specification.

This invention relates to hydrocarbon motors and particularly to means for heating the mixture passing from the carburetor to the motor cylinders.

More specifically, the invention constitutes an improvement over my invention described in application Serial No. 323,627, filed September 13, 1919.

One of the objects of the invention is to improve the action of a heater device of the type described in said pending application.

Another object of the invention is to connect the air inlet of an auxiliary carburetor with the auxiliary air intake of the main carburetor of the motor.

Another object of the invention is to better control the richness of the mixture of a carbureting means such as shown in said application.

Other objects of the invention will appear from the following description taken in connection with the drawings which form a part of this specification and in which

Figure 1 is a vertical section through a heater and carbureting means embodying the invention, and

Figure 2 is a transverse section on the line 2—2 of Figure 1.

Referring to the drawings, 10 represents a hydrocarbon motor, a portion only of the cylinder casting being shown on the drawing. This may be a single or a multi-cylinder motor. The motor carburetor or fuel mixing device is indicated generally by the numeral 11, and in the form shown, which is of the well known Packard type, 12 is the mixing chamber, 13 the Venturi mixing tube, 14 the fuel nozzle arranged in the tube 13, 15 the main air intake and 16 the auxiliary air intake. A manually adjustable valve 17 is arranged in the main air intake, an arm 18 and rod 18' being provided to effect the adjustment. A poppet valve 19 yieldingly closed by springs 20 governs the amount of air passing through the auxiliary inlet 16. For the purpose of choking the carburetor, that is of shutting off practically all of the air thereto, the valve 17 may be turned to

the position shown in dotted lines so that it practically closes the main air intake 15 and bears against an extension 21 on the valve 19 thereby holding the latter valve positively closed.

The fuel nozzle 14 may be supplied with gasoline or other fuel by any well known means, and in the present form it is supplied from an adjacent float chamber 27, a passage 28 leading to the lower end of the nozzle. A float 29 operates through pivoted levers 30 on a valve 31 to maintain a substantially constant level of gasoline in the float chamber, this level usually being arranged as shown slightly below the top of the nozzle 14. The valve 31 seats at 32 and controls the supply of gasoline entering the chamber from the main fuel line or pipe 33.

It will be understood that when there is a depression in the mixing chamber 12 as 75 by reason of the suction from the motor, air will be drawn through the Venturi tube 13 past the nozzle 14 from which gasoline or other fuel will flow. The gasoline and air will mix as they pass upwardly through the 80 tube 13 and will be further mixed with the air drawn into the mixing chamber 12 through the auxiliary air inlet 16, the valve 19 opening slightly because of the suction. The extent of valve opening will depend 85 upon the suction and consequently approximately the correct mixture will be supplied to the motor at all speeds. When the valves 17 and 19 are closed only a slight amount of air will pass the valve 17 and none will pass 90 the valve 19, and the greater suction thus produced on the fuel in the nozzle 14 will result in a very rich mixture in the chamber 12, this mixture being particularly adapted for starting purposes or when the motor is 95 cold.

The mixing chamber of the carburetor 11 is adapted to be connected to the motor so that the mixture may be supplied to the cylinders of the latter. As shown, this connection is an intake pipe 22 in the shape of an elbow having a flange 23 for connection to a flange 24 on the carburetor, and a flange 25 for connection to the motor 10. Somewhere in the passage between the carburetor 100 and the motor a throttle valve is arranged, and in this form a butterfly valve 26 is pivotally mounted near the upper end of the mixing chamber 12.

By this construction the intake pipe or 110

conduit 22 becomes a continuation of the mixing chamber 12 and the mixture formed by the carburetor 11 will be drawn past the throttle valve 26 and through the mixture 5 passage or conduit formed by the pipe 22 into the motor cylinders. It is this mixture which it is desired to heat in order that the particles of gasoline or other fuel being carried over may be volatilized and the mixture 10 not permitted to condense on the walls of the passage.

Another carburetor or fuel mixing device is indicated generally by the numeral 34 and is for the purpose of supplying a combustible mixture through a pipe 54 to a combustion chamber 55 which is formed as a jacket to the intake pipe 22. The combustion chamber 55 is partly formed by a plug 55' which is secured to it and which is provided 20 with a spark plug 59 having sparking points 60, 61 and with an observation window 55''. The inlet from the pipe 54 to the combustion chamber 55 is through an adjustable inlet passage 57 and a screen 58, 25 and the outlet from said chamber into the intake header 22 is through a passage 56 in a plug 62.

From the above it will be observed that the suction of the motor will draw a charge 30 of combustible mixture from the auxiliary carburetor 34 through the pipe 54 into the combustion chamber 55 where this charge will be fired by the spark plug 59 and the hot burnt gases discharged into the intake 35 pipe. Thus the intake pipe will be heated and the mixture passing from the carburetor 11 will absorb some of this heat, as well as being directly heated by contact with the hot burnt gases coming from the combustion 40 chamber 55.

The carburetor 34 is shown mostly in elevation and it will be understood that in detail it may be of the form shown in said application Serial No. 323,027. It may draw 45 its gasoline or other fuel from any suitable source, but in the form shown it is arranged in connection with the float chamber 27 and receives gasoline therefrom. It is in fact mounted directly upon the cover 35 of the 50 float chamber, said cover also having a vent 36 for maintaining atmospheric pressure in the chamber and permitting inflow of air for the use of the carburetor 34 when the same is of the compensating type illustrated 55 in said pending application.

This carburetor 34 comprises a piece 37 which is threaded into the top of the cover 35 and has an extension 42 into the float chamber 27. Gasoline is drawn from the 60 float chamber through a central passage 44 and there are also passages 51 for supplying air to the carburetor in addition to that which it may receive from the float chamber. Air is supplied to the passages 51 by 65 a pipe 50 which, in the present invention,

communicates with or extends to the auxiliary intake 16 of the main carburetor 11, as shown at 52. Thus when the carburetor 11 is choked for starting, that is when the valve 17 has been moved to the position 70 shown in dotted lines, which also holds closed the valve 19, practically no air will be supplied to the auxiliary carburetor 34 through the pipe 50 and said auxiliary carburetor will then depend for air entirely 75 upon the small amount it can receive from the float chamber. Therefore, the mixture supplied by the carburetor 34 will at this time be very rich and thus facilitate starting the heater chamber 55 in operation in 80 very cold weather. Also, it will be seen that after the motor has started and it is necessary to immediately move the valve 17 to permit some air to be drawn through the carburetor 11, the choking of the tube 50 85 will still be in effect to a large extent because of its connection with the auxiliary inlet 16 which is still controlled by the valve 19, this valve being held closed by springs 20, the tension of which will be kept tight 90 until the motor warms up. As the motor warms up the springs 20 will be released to some extent and the valve 19 permitted to open more easily. This will supply more air to the carburetor 11 and likewise permit of a greater amount of air being supplied to the carburetor 34. 95

Other forms of devices than that shown may be made without departing from the spirit or scope of the invention.

Having thus described my invention, what I claim and desire to secure by Letters Patent is:

1. In a hydrocarbon motor, the combination with the motor intake conduit, of a carburetor connected thereto and having main and auxiliary air intakes, a heater device, a carburetor for supplying mixture to said device, and means for supplying air to the latter said carburetor by a connection to the auxiliary intake of the first carburetor. 105

2. In a hydrocarbon motor, the combination with the motor intake conduit, of a carburetor having an automatically controlled air intake, of a second carburetor, and an air connection from said air intake of the first carburetor to said second carburetor. 115

3. Carbureting means comprising a mixing chamber, main and auxiliary air intake means communicating with said chamber, a float chamber, a fuel nozzle fed by said float chamber and discharging into said mixing chamber, a mixing device connected to said float chamber to receive liquid fuel therefrom, and an air connection for said device leading from said auxiliary air intake means. 120

In testimony whereof I affix my signature.

LIONEL M. WOOLSON.
